United States Patent

Des. 238,008

Patented Dec. 9, 1975

238,008

HAND HELD DETANGLER

Bernard B. Bluestein, Des Plaines, and Norman A. Stein-kamp, Chicago Heights, Ill., assignors to Sunbeam Corporation, Chicago, Ill.

Filed July 15, 1974, Ser. No. 488,549

Term of patent 14 years

Int. Cl. D28—03

U.S. Cl. D86—8

FIG. 1 is a perspective view of a hand held detangler showing our new design;

FIG. 2 is a top plan view thereof;

FIG. 3 is a back side elevational view thereof;

FIG. 4 is a front end elevational view thereof;

FIG. 5 is a rear end elevational view thereof; and

FIG. 6 is a bottom plan view thereof.

The dashed lines in FIGS. 3 and 6 indicate continuity of the teeth that have been omitted for convenience of illustration.

We claim:

The ornamental design for a hand held detangler, as shown and described.
